PROCESS AND PRODUCT FOR CONTINUOUSLY WRAPPING ICE CREAM OR OTHER PRODUCTS

August J. Asmussen and Thomas G. Paolillo,
Brooklyn, N. Y.

Application October 29, 1934, Serial No. 750,432

12 Claims. (Cl. 93—82)

Our invention relates to an improvement in a process for continuously wrapping ice cream or other products and its novelty consists in the steps of said process and the products produced 5 thereby.

There is now on the market a paper tube forming and filling machine for wrapping ice cream or other products continuously, known as the Clarence W. Vogt machine and made under United 10 States Patents Nos. 1,801,740, 1,801,863, 1,801,864 and 1,906,183 but it uses glue in securing the wrapper together. This is objectionable because it is unhygienic because the glue contaminates the material in the container and also because it 15 either does not stay fastened with sufficient security if inadequately glued or is too difficult to remove if glued too much.

Our process solves these problems and furnishes a new wrapper or container which is positively locked or fastened together so that the fastening is very strong against inside pressure but fragile when pulled apart on the outside as is desired in unwrapping the container.

Referring to the drawings Figure 1 is a top 20 plan view of our mechanism as it is attached in position on said patented Vogt paper tube forming and filling machine.

Figure 2 is a side elevation of the lifting mechanism of the upper shoe.

Figure 3 is a perspective of the complete paper tube or container made by our process and apparatus.

Figure 4 is a vertical cross sectional view on the line 4—4 of Figure 1.

Figure 5 is a horizontal cross sectional view of Figure 4 on the line 5—5.

In the drawings 6 is a hygienic ice cream or other material filling tube of said Vogt paper tube forming and filling machine rigidly mounted 40 in a fixed position by means of the clamping bracket 7 of usual construction, which is rigidly secured at 8 to a floor or base 9 in the usual well known manner. An inner forming tube 10, also held rigidly in position by brackets 7, is mounted 45 over said hygienic tube 6 with a very slight insulating space of air between. A lower or bottom shoe 11 constituting the outer lower half of an outer forming tube is held rigidly in a fixed position by means of supporting brackets 12 secured 50 in the usual well known manner at 13 to the base or floor 9 so that it is immediately around the lower half of the inner forming tube 10. An upper shoe 14 completing the outer forming tube with the lower shoe 11 is mounted thereon by 55 means of arms 15 which terminate in plates 16

at one end which are rigidly secured at 17 to the said upper shoe 14 and are pivoted by means of the usual bearings on shafts 18 in the heads of brackets 19 rigidly secured at 20 in the well known manner to the plate or floor 9. These arms 15 are counterbalanced by adjustable weights 21 mounted thereon in the usual well known manner with set screws 22, so that said upper shoe 14 can be raised and lowered quickly and easily. The upper shoe 14 also has slotted ears 23 which are 10 in alignment with similar ears 24 integral with the lower shoe 11 and which carry clamping bolt members 25 with a spring member 26 under the ears 24 on said bolt so as to permit of an easy riding of said upper shoe 14 on said lower shoe 11 15 as the paper tube being formed passes therethrough.

A pair of circular plates 27 having puncturing or piercing teeth 28 arranged around the entire outer periphery of said circular plates are 20 mounted on shafts 29 so as to rotate freely thereon, and said shafts 29 are rigidly secured at 30 in the usual well known manner to the arms 31, which in turn are pivoted at 32 in the usual manner on the posts 33 so as to turn freely thereon, 25 and said arms 31 have handles 34 extending from the outer ends thereof so that said toothed plates 27 can be swung out of engagement as desired. There are also limiting elements 35 rigidly secured at 36 to the plate or floor 9 so as to prevent the 30 toothed plates 27 from swinging beyond the desired point for effecting the piercing of the paper tube and interlocking of the same. The teeth 28 have their highest point 37 in the rear portion of the tooth 28 as it rotates with the tubular container 35 being formed in our device and the high point 37 runs down to a low point 38 at the front of the tooth 28 as it rotates.

There is a slot 39 cut through the upper shoe 14 at the right side of Figure 4 as shown in the 40 drawings, and a narrow shearing slot 39' on the side of the inner forming tube 10 for the teeth 28 of the plate 27, and a slot 40 on the left hand side of Figure 4 through the lower shoe 11 and a narrow shearing slot 40' on the side of the inner 45 forming tube 10 for the clearance of the teeth 28 on the plate 27 on that side.

In operating our device as described in conjunction with the Vogt paper tube forming and filling machine, a strip of paper 41 will be run 50 from the usual reel holding the same, not shown herein, over the inner forming tube 10 and the shoe 14 will be raised by means of the pivoted arms 15 so that said upper strip of paper 41 will be in position over said inner forming tube 10, 55

and an under strip of paper 42 will be drawn through over the under side of the inner forming tube 10 and under the lower outer shoe 11, and as there are slots 43 and 44 the under strip of 5 paper 42 will project through said continuous slot 43 to form a flange 45, and the upper strip of paper 41 will pass through the continuous slot 44 forming an outer flange 46. It will also be apparent that the upper strip of paper 41 over- 10 laps the under strip of paper 42 at 47 and that the under strip of paper 42 overlaps the upper strip of paper 41 at 48. These overlapping portions 47 and 48 are where we desire to secure the two strips of paper 41 and 42 together to form 15 the cylindrical container or tube for holding the ice cream or other product to be filled thereinto.

The two strips of paper 41 and 42 are gripped by the usual Vogt conveyor (not shown) and pulled through the mechanism described in an 20 absolute synchronism, thereby forming the continuous tubular paper tube or container for filling.

Our device locks and securely fastens together these two formed semi-tubular members 41 and 25 42 by means of the teeth 28 of the plates 27 which rotating in the same direction with the line of travel of said paper impinge upon said paper and pressing the same against the shearing edges of the slots 39' and 40' form a continuous series 30 of punches or piercings through each side of the said overlapped portions 47 and 48 of the semi-tubular paper members 41 and 42, whereby the series of paper tabs 49 are projected inwardly and backwardly of the line of movement. These inwardly projected tabs 49 are flattened down as 35 the tube is drawn on over the inner forming tube 10.

As the tube thus formed and secured together is filled with ice cream at a point beyond the 40 Figure 1 shown herein where the hygienic tube 6 ends within said paper tube, the ice cream or other product will fill said paper tube, and as the inwardly turned tabs 49 have been somewhat flattened down they will be further flattened 45 down and the slight openings filled by ice cream or other product being filled into said paper tube.

As the continuous tubular container formed thus by the interlocking tabs 49 in the overlapping side edge portions of paper strips 41 and 42 50 is filled by ice cream or some other product, it is drawn on to a point where it is cut off in desired lengths and carried forward for further treatment as may be desired.

It will be particularly noted that the entirely 55 novel container as shown in Figure 3 resulting from our process and apparatus has a continuous row of tabs 49 on each side projecting inwardly slightly and which, as the container is put under pressure from the inside, causes said interlocked tabs to merely pull sidewise, causing a binding of the projecting tabs on the sides of the double hole in the two strips 41 and 42, and that the strength of this interlocking in that direction is more than could be overcome by any intended 60 use of said container for ice cream or other product.

However, if the two flanges 45 and 46 are taken 70 between the fingers of each hand and pulled gently, the tabs 49 are easily and without resistance lifted up and out of the holes made by piercing strips 41 and 42 because of the direction of the pull or tension. Thus the novel container 75 formed by our process and apparatus completely solves the problem of a hygienic container having more than the recognized strength for

holding the ice cream or other product perfectly for shipment and handling but being subject to quick and easy opening for use.

It will be apparent that a metal adaptable to the piercing and bending out of tabs may be used 5 in our process instead of a paper-like material and that many variations may be made in our invention without departing from the spirit and intent of the same.

We claim:

1. The process of continuously forming a cylindrical container from two continuously pulled strips of paper which consists of pulling the two strips simultaneously into superimposed relationship over a cylindrical forming tube, one above 15 and one below, and locking said strips together continuously along their overlapped side edges by a continuous row of interlocked punched out pairs of tabs of said overlapped strips of paper.

2. The process of continuously forming a cylindrical container comprising drawing an upper and a lower continuously fed strip of paper-like material into semi-cylindrical continuous members over a cylindrical forming tube with each strip having a continuous flange formed on opposite side edges and continuous overlapping portions adjacent said flanges and fastening same together by a continuous row of interlocked tabs punched out of said overlapped portions.

3. The continuous process of making a container of paper which consists of pulling an upper and lower strip into engagement with a cylindrical forming tube, the upper strip around the upper half and the lower strip around the lower half of said tube thereby forming two continuous longitudinal halves and continuously securing their overlapping side edges together by forming a continuous row of interlocked tabs from said overlapped portions.

4. A new product of manufacture comprising 40 a container formed of a paper-like material from two parts having overlapping adjoining edges secured together by means of a row of interlocked tabs formed from said overlapped portions and a continuous flange along the entire length of 45 each of said overlapping edges.

5. A new product of manufacture comprising a cylindrical device formed of a paper-like material from two parts having overlapping adjoining edges secured together by means of a row of 50 interlocked tabs formed from said overlapped portions and flanges extending along the entire length of each of said overlapping adjoining edges.

6. The process of continuously forming a cylindrical container from two continuously pulled strips of material which consists of pulling the two strips simultaneously into superimposed relationship over a cylindrical forming tube, one above and one below, and locking said strips 60 together continuously along their overlapped side edges by a continuous row of interlocked punched out pairs of tabs of said overlapped strips of material and forming flanges extending along the entire length of each of said overlapping adjoining edges.

7. The process of continuously forming a cylindrical container which consists of simultaneously pulling two strips of paper over a cylindrical forming tube, one above and one below, and locking said strips together continuously along their overlapped side edges by a continuous row of interlocked punched out portions of said overlapped strips of paper.

8. The process of continuously forming a cylin- 75

drical container which consists of pulling an upper and a lower continuously fed strip of paper-like material simultaneously over a cylindrical forming tube, one above and one below, and forming same into semi-cylindrical continuous members with each strip having a continuous flange formed on opposite side edges and continuous overlapping portions adjacent said flanges and fastening same together by a continuous row of interlocked ruptured projections of said overlapped portions.

9. The continuous process of making a container of paper by synchronously pulling an upper and lower strip of paper respectively over and under a forming tube and forming two continuous longitudinal halves and continuously securing their overlapping side edges together by forming a continuous row of interlocked ruptured projections from said overlapped portions.

10. A new product of manufacture comprising a container formed of a paper-like material from two parts having overlapping adjoining edges secured together by means of a row of interlocked ruptured projections formed from said over-

lapped portions and a continuous flange along the entire length of each of said overlapping edges.

11. A new product of manufacture comprising a cylindrical device formed of a paper-like material from two parts having overlapping adjoining edges secured together by means of a row of interlocked ruptured projections formed from said overlapped portions and flanges extending along the entire length of each of said overlapping adjoining edges.

12. The process of continuously forming a cylindrical container which consists of simultaneously pulling two strips of material over a cylindrical forming tube, one above and one below, and locking said strips together continuously along their overlapped side edges by a continuous row of interlocked punched out pairs of ruptured projections of said overlapped strips of material and forming flanges extending along the entire length of each of said overlapping adjoining edges.
